GAME HORSESHOE

Charles D. Poole, 3311 Dumas Drive,
Nashville, Tenn. 37211

Filed June 13, 1972, Ser. No. 262,264

Term of patent 14 years

Int. Cl. D21—01

U.S. Cl. D34—5 GP

FIG. 1

FIG. 2

FIG. 3

FIG. 4

FIG. 5

FIG. 1 is a front elevational view of the game horseshoe of my design;

FIG. 2 is a bottom plan view of the game horseshoe shown in FIG. 1;

FIG. 3 is a top plan view of the game horseshoe shown in FIG. 1;

FIG. 4 is a right end elevational view of the game horseshoe shown in FIG. 1; and

FIG. 5 is a left end elevational view thereof.

The rear elevational view of the game horseshoe embodies the same configuration as shown in the front elevational view in FIG. 1.

I claim:

The ornamental design for a game horseshoe, as shown and described.
